STRIP-SERVING MACHINE

Gisbert Loewenberg, Chicago, Ill., assignor to
Metal Specialties Manufacturing Co., Chicago,
Ill., a corporation of Illinois

Application April 11, 1934, Serial No. 720,108

7 Claims. (Cl. 164—42)

This invention relates particularly to strip-serv-
ing machines, especially adapted to the pur-
pose of serving gummed tape. If desired, the
machine may be used to serve ungummed tape,
5 in which case the moistening device illustrated
may be replaced by any suitable adhesive-apply-
ing device.

The primary object is to provide a strip-serv-
ing machine of improved general construction
10 which may be power-driven and is adapted to
serve tape and sever the same in any desired
length.

The invention is illustrated in a preferred em-
bodyment in the accompanying drawings, in
15 which:

Fig. 1 is a side elevational view of a machine
embodying the invention; Fig. 2, a plan view of
the same; Fig. 3, a front elevational view of the
same; Fig. 4, a vertical sectional view, taken as
20 indicated in line 4 of Fig. 3; Fig. 5, a vertical
sectional view taken as indicated at line 5 of
Fig. 3; Fig. 6, a vertical sectional view, taken as
indicated at line 6 of Fig. 3; Fig. 7, a fragmentary
25 sectional view, taken as indicated at line 7 of
Fig. 6; Fig. 8, a broken plan sectional view, taken
as indicated at line 8 of Fig. 6; Fig. 9, a frag-
mentary sectional view, taken as indicated at
line 9 of Fig. 6 and showing diagrammatically
30 the wiring diagram for an electric motor; Fig. 10,
a vertical sectional view, taken as indicated at
line 10 of Fig. 5; Fig. 11, a fragmentary sectional
view taken as indicated at line 11 of Fig. 4;
Fig. 12, a fragmentary sectional view of the cam-
35 adjusting lever, taken as indicated at line 12 of
Fig. 4; Fig. 13, a broken vertical sectional view,
similar to Fig. 6, showing the starting lever in
switch-closing position; Fig. 14, a similar view
showing the operating mechanism in position to
40 serve a strip longer than required by the cam ad-
justment; and Fig. 15, a vertical sectional view
showing the knife mechanism, taken as indicated
at line 15 of Fig. 13.

In the preferred construction, which is illus-
trated, A designates a frame, or casing, comprising
45 a base-member A' and a cover-member
A² pivotally connected at its rear end-portion
with the base A'; B, a rotatable main
shaft journaled in the member A' and equipped
50 with a rigidly connected pawl-carrier B' adapted
to drive a ratchet wheel B² which is rigidly
connected to a feed-wheel B³ journaled on
the shaft B; C, a spring-pressed additional
feed-roll which co-acts with the feed-wheel B³;
55 D, a roll of gummed tape mounted in the rear por-
tion of the casing A, from which a strip of paper

passes to the feed-roll; E, cutting mechanism
comprising a cutter-equipped lever E', a link E²,
and a trip-lever E³, which has its lower end piv-
oted to the frame A'; F, a finger-operated start-
ing lever; G, a knife-switch wired to a motor G';
H, a water-fount removable through the open
front end of the casing, and equipped with a
capillary member H' adjustably mounted there-
in; and a pivotally mounted pressure-member H²
which coacts with the upper end of the mem-
ber H'.

In the embodiment of the invention shown,
the frame A is composed of elongated hollow
castings mounted one upon another. The main
part of the frame comprises the base casing A', 15
and the cover A² is used to enclose the chamber
which holds the roll of tape, and may be omitted,
if desired. The casing A' comprises a perimetral
wall which provides side walls and end walls.
The casing is open at the top and bottom. 20

The cover A² is connected at its rear end by a
pivot 16 with the upper rear portion of the cas-
ing A'. The cover is in the form of a hollow cast-
ing which is provided with side walls 17 and a
curved top wall 18 which also form the front 25
and rear walls of the cover. The lower edges
of the side walls 17 of the cover rest upon the
upper edges of the side walls 19 of the casing A'.
The front wall of the cover is cut away to provide
a space 20 which forms with the top wall of the 30
base casting 21, a throat through which the
paper strip is fed. A gravity presser member 21^a
is provided to press the strip of tape flat against
the top wall 21 of the frame A'. 35

As shown in Fig. 1, the side walls 17 and 19 35
are struck outwardly at 22 to provide vertical
slots in which the shaft 23 of the web roll may
travel vertically. As shown in Fig. 5, the mem-
ber A' is equipped with a curved top wall 24 on
which the roll of gummed tape may rest. The 40
main drive-shaft B, as shown in Fig. 5, is
equipped with a gear 25 which is engaged by a
worm 26 provided on a shaft 27 which is driven
by shaft 28 of the motor G'. The shaft 27 is
journaled in the gear box 29, which is suspended 45
from the shaft B by means of a pair of upwardly
extending arms 30. The motor is suspended
from the frame member A' by means of screws
31 in such manner that in case it is desired to
examine the motor, said screws may be removed 50
and the motor swung downwardly out of the
casing, without disconnecting the gears from the
shaft B.

The pawl-carrier B' is rigidly connected to the
shaft B by means of a bolt 32. The outer end 55

of the pawl-carrier is equipped with a pivot-member 33 which provides a stud 34 upon which the pawl 35 is journaled. A coil spring 36 is wrapped about the pivot member 33 and has one end connected to a projection 35^a on the pawl and the other end with a projection 37 on the pawl-carrier. Said spring urges the pawl into engagement with teeth 38 provided on the ratchet wheel B². As best shown in Figs. 10 and 11, the feed-wheel B³ and the ratchet B² are mounted on a bushing 39 which is journaled on the shaft B.

A bushing 40 is also journaled on the shaft B and carries a rigidly connected cup-shaped arcuate cam-member 41 which is adapted to be engaged by the outer end-portion of the pawl 35, upon rotation, and disconnect the pawl from engagement with the ratchet teeth. The cam may be adjusted angularly by means of a finger-member 43 which may be adjusted in a slot 44 provided in a member 45 which is secured to the side walls of the casing A' by means of screws 46. The slot is provided with enlarged portions 44^a to hold the member in a desired position. In order to move the member the finger piece 43 is depressed on its arm 43^a, which is rigidly connected to the shaft B, against a compression spring 47 and swung to a desired position where the member 43 is allowed to project from one of the openings 44^a. Thus it will be understood that by angularly adjusting the member 43 the length of the arc through which the ratchet is engaged may be determined, and accordingly the length of strip served by the feed-wheel during each revolution of the shaft B may be adjusted as desired.

At the right-hand end of the shaft B, shown in Fig. 10, a cam member 50 is rigidly connected by means of a bolt 50^a. A spacing collar 51 is provided between the cam-member and the wall 40 of the machine. The cam is provided with a projection 52 which is adapted to engage the arm E³, as will be explained below.

The spring-pressed idle-feed roll C is journaled on a horizontal pin 53, as shown in Fig. 10, carried by a sheet-metal member 54, which is provided at its lateral edges near its rear end with upturned lugs pivotally mounted on a shaft 55 (Fig. 5). A spring 56 encircles the shaft 55 and urges the roll C into engagement with the feed-wheel B³, as will be readily understood.

As shown in Fig. 5, the roll of gummed tape, preferably, is wound on a core 56, carried by shaft 23 upon which are disposed a pair of spring plates 57 which can be adjusted to provide the desired amount of friction on the sides of the core 56. The plates 57 are of elongated form and fit freely within the cover A², but do not rotate when the tape is withdrawn.

The cutting mechanism E will be understood by reference to Figs. 1-5 and 15. The front portion of the top wall 21 of the casing A' is cut away and provided with a knife-edge 60. The horizontally disposed blade-carrying lever E' has one end connected to the frame A' by means of a pivot 61. A leaf spring 62 urges the blade into sharpening engagement with the member 60. The lever E' is normally held in elevated position by means of the link E² which is pivotally connected at its lower end to the trip member E³ which is urged upwardly by means of a tension spring 63. As indicated in Fig. 6, the trip-member is normally in a position to be engaged by the stud 52 provided on the cam member 50 and, accordingly, it will be understood that when the cam is rotated counter-clockwise the arm will be

depressed to the dotted position indicated in Fig. 6 and the cutter blade will be actuated to sever the tape.

When the operating lever F, which is pivoted to the frame A' at 64, is depressed, it forces the knife-switch G to complete the motor circuit (as shown diagrammatically in Fig. 9) and the shaft B is put in motion. As shown in Figs. 6, 13 and 14, the trip-arm E³ may be held in the path of the projection 52 by means of a cam-member 65 which is pivoted to the frame A' at 66. The cam makes a lost motion connection with the lever F by means of a link 67 and pivot-member 67^a. The cam is urged against a stop 68 by means of a tension-spring 69. The starting-lever F is urged upwardly by means of a tension spring 70.

In case it is desired to serve a strip of tape of a greater length than the machine happens to be adjusted for, the operator may hold down the operating arm F. This will move the arm E³ out of the path of the projection 52 and permit the ratchet wheel to be re-engaged by the pawl on each revolution without operating the cutter. As a safety measure, to prevent the arm E³ from being permitted to swing back into the path of 52 by inadvertent release of the arm F, a latch-arm 71 is pivoted to the frame at 71^a. The purpose of this latch-arm is to prevent the projection 52 from striking the end of the lever E³ and jamming the machine on center. The front end of the latch is urged into engagement with a tooth 65^a of the cam 65 by means of a tension spring 72. The cam 50 has a cut-away portion diametrically opposite from the projection 52 and has a curved portion 73 to engage the rear end of the latch-arm and release the cam 65 when the projection 52 has passed the danger point.

Referring now to the switch G, it will be understood that it is wired in series with a source of power and the motor by means of wires 80 and 81. The knife of the switch 82 is mounted on an insulated arm 83 which is pivoted to the frame at 84 and is equipped with a tension spring 85 which is mounted in toggle-fashion so as to urge the blade into open or closed position. The lower end of the arm 83 is provided with a projection 86 which is engaged by the member E³. Thus, it will be understood that when the projection 52 depresses the trip-member E³ the switch will be thrown open automatically.

The lever-mechanism described above is made up in a unit enclosed in a housing 87. This housing is removably secured within the frame A' by means of screws 88.

The water fount G and moistener H' as well as the pivotally mounted presser-member H², are of the same type shown in Herman patent 1,849,759. The fount may be removed from the machine by depressing a finger-member 90 provided in the front of the casing A'.

To operate the machine the finger-member F is depressed. This action closes the switch G and starts the motor G' which causes the pawl-carrying member B' to rotate. The pawl is urged into engagement with the teeth in the ratchet wheel B², and the feed-wheel B³, cooperating with the roll C, feeds forwardly a strip of tape until the tail of the pawl 35 comes into engagement with the arcuate cam 41, which releases the pawl from driving the feed-wheel. The projection 52, rigidly connected to the shaft B, continues to rotate, however, and engages and depresses the lever E³. The latter action causes the

cutter blade to sever the projecting strip and opens the switch G. The momentum of the motor is sufficient to carry the projection 52 far enough to permit the member E³ to resume its 5 normal position shown in full lines in Fig. 6. In case an additional length of unsevered tape is desired, the operator may either hold the finger-member F depressed or may again trip it before the cutter blade is actuated. This will cause the 10 pawl-carrier to continue to rotate and the feed-wheel will continue to feed the strip in spurts. During each revolution the feed-wheel is partially rotated and then disconnected, which causes the intermittent or spurt feeding action. 15 The foregoing detailed description is given for clearness of understanding only, and no unnecessary limitations should be understood therefrom, but the appended claims should be construed as broadly as permissible, in view of the 20 prior art.

What I claim as new and desire to secure by Letters Patent is:

1. In a machine of the character set forth: a frame; a shaft journalled in said frame and 25 provided with a projecting arm; a strip-feeding wheel journalled on said shaft; a ratchet and pawl device interposed between said shaft and strip-feeding wheel; means for releasing said pawl from the ratchet during part of each revolution of the shaft; cutter-means for severing a 30 length of strip advanced by said feeding wheel; a lever disposed in the path of said projecting arm to actuate said cutter-means; and means for moving said lever out of the path of the projecting arm to avoid operation of the cutter means. 35

2. A device as specified in claim 1, including timing means for preventing return movement of the lever into the path of the projecting arm 40 during a portion of the cycle of rotation of the shaft.

3. A machine of the character set forth: a frame; a shaft journalled in said frame and provided with a cam and a projecting arm; a strip-feeding wheel journalled on said shaft; a ratchet and pawl device interposed between said shaft and strip-feeding wheel; means for releasing said pawl from the ratchet during a part of each revolution of the shaft; cutter means for severing 45 a length of strip advanced by said feeding wheel; a lever disposed in the path of said projecting arm to actuate said cutter-means; an electric motor geared to said shaft; a switch for controlling said motor; a finger-operated member for closing said switch; a latching-dog connected to 50 said finger member and pivotally mounted on said

frame so as to move said lever into and out of the path of the projecting arm; and a latching member pivotally mounted on said frame with one end engaging said cam and the other adapted to engage said latching-dog to prevent the lever 5 from returning into the path of the projecting arm during a portion of the cycle of rotation of said shaft.

4. A device as specified in claim 3, in which the switch comprises a pair of contact members, 10 a pivotally mounted contact closing member adapted to be thrown open by the operation of the cutter lever, and spring-means mounted in toggle-fashion for urging said contact closure member into either open or closed position. 15

5. In a strip-serving machine: a frame; a shaft journalled in said frame and equipped with a strip-feeding wheel and a gear wheel; a worm wheel journalled in a gear box pivotally suspended from said shaft so that said worm wheel and gear are 20 in driving engagement; an electric motor in driving engagement with said worm; and means for releasably supporting said motor within the lower portion of said frame so that the motor and gear box may be swung about the shaft without being 25 disconnected from each other.

6. In a machine of the character set forth: a frame; a shaft journalled in said frame; a strip-feeding wheel journalled on said shaft; a ratchet and pawl device interposed between said shaft and strip-feeding wheel; an electric motor geared 30 to the shaft; a knife switch for controlling said motor; cam-means, adjustable circumferentially of said shaft, for releasing said pawl from driving engagement with said ratchet device during 35 part of each revolution of the shaft; and means, operable by said shaft, for automatically opening said switch after a complete rotation of the shaft.

7. In a machine of the character set forth: a 40 frame; a driving shaft journalled therein; a feed-wheel provided with ratchet teeth, journalled on said shaft; a driving arm mounted on said shaft and provided with a pivotally mounted pawl adapted to engage said ratchet teeth; an electric 45 motor geared to said shaft; a knife-switch for controlling said motor; arcuate cam-means adjustable circumferentially of said shaft for releasing said pawl from driving engagement with the ratchet teeth during part of each revolution 50 of the shaft; a finger-operated member for closing said switch; and tripping-means actuated by said shaft for automatically opening said switch after disengagement of the pawl.
